CELL TYPE FILTER ELEMENT

George D. Burley, Cleveland, Ohio, assignor, by
mesne assignments, to Fram Corporation, East
Providence, R. I., a corporation of Rhode Island

Application June 27, 1947, Serial No. 757,630

5 Claims. (Cl. 210—169)

1

This invention relates to a cell type filter element for collecting contaminant from liquids to be filtered therethrough.

In the use of a cell type filter element such as that made from some porous stock, such as paper, different shapes of members stacked one upon the other have been provided. In many instances, the shapes become complicated and thus the cost of cutting out tools for producing the same is expensive. Also, in the more complicated types of sheet members, the structure may be weak in parts and thus apt to rupture. Also some warping of the plates at the ends of a stack of sheet members is apt to occur due to expansion of the members if the stack is supported near its outer periphery.

One of the objects of this invention is to provide a shape of sheet member which may be used in one form throughout the stack, thus making unnecessary the formation of two shapes for the use in the element.

Another object of this invention is to simplify the shape of each of the filtering members of identical configuration to reduce cost of dies or the cutting out tools for the members.

Another object of the invention is to provide a more rugged shape of sheet member for serving in the stack of members.

Another object of the invention is to provide an arrangement of members in the stack with a support therefor so that the possibility of warping the end plates of the stack is reduced to a minimum.

With these and other objects in view, the invention consists of certain novel features of construction as will be more fully described and particularly pointed out in the appended claims.

In the accompanying drawings:

Fig. 1 is a sectional view of a filter, showing the element in position in the case;

Fig. 2 is a perspective view of one of the sheet members of the element;

Fig. 3 is a top plan view of two or more of the sheet members piled one on top of the other.

In proceeding with this invention, I form in any suitable manner, such as by cutting out from a sheet stock filter medium which may be paper or cardboard, a member of the shape shown in Fig. 2 and by oppositely positioning these members in piling them one upon the other so that openings through the members will register, I provide a stack. The area about the opening is of rugged structure and provides the location where pressure may be exerted by expansion of the members and at this location I support the end plates by

2

means of rods which serve to locate as well as to tie together the stack of members at a well supported location.

With reference to the drawings, 10 designates 5 a metal case usually of cylindrical construction, although not necessarily so, which has a center tube 11 secured to the bushing 12 whose flange 13 is welded to the outer bottom of the casing. This bushing is threaded as at 14 for connection to a conduit for leading the filtrate from the casing. A drain plug 15 closes an opening 16 through a boss 17 also in the bottom portion of the filter. An inlet opening is designated 18 and is threaded for connection to a conduit to supply contaminated liquid to the casing. The cover 19 is sealed upon the upper edge of the casing by gasket 20 and is held in position by headed screw 21 having threads at 22 to engage the inner surface of the upper end of the center tube 11.

20 The filter element about which this invention centers is designated generally 25 and consists of a plurality of sheet members 26 shown in perspective in Fig. 2. In this particular case, the outer periphery of the member 26 is circular so that the element 25 is generally cylindrical, although other shapes may be provided. The sheet member 26 is formed of any suitable filter medium such as paper, chipboard, cardboard, or of a felted mass, of a weight which will be sufficient to be self-supporting so that the member may extend generally horizontally without drooping or bending so as to maintain a space between it and like members spaced from it. The paper, chipboard or other filter medium of this member will transmit filtrate through it in the plane parallel to its surface. The outer edge of this member 26 designated 27 is the shape of a half circle and covers an arc of substantially 180 degrees from the center of opening 28 so that the portion which extends 30 from the opening 28 forms a web portion 29 as shown in Fig. 2. There is also provided in addition to the half circular area a radiating portion 30 which surrounds the opening 28 with sufficient stock so as to provide a good rigid part of the member 26 which will not easily break out between the opening 28 and the edge of this portion 30. The opening 28 is illustrated as rectangular and serves by reason of this shape for the initial alignment of the members when in stacked relation.

40 The distance between the corner 31 and the periphery 32 of this portion 30 is the shortest distance from the periphery to the opening and thus serves as the point of initial filtering through the paper stock of the member.

45 The members 26 are stacked alternately in op-

50

posite relation with reference to the long axis of the rectangular opening 28 so that the rectangular openings in adjacent and contacting members will be in alignment and by reason of this stacking there is provided cells 35 between the web portions 29 of the members on either side of the diametrical line through the long axis of the rectangular opening 28. In order that the stack may be maintained in alignment and also held in assembled relation, openings 36 are provided in each of the members 26 on one side of the opening 28 and notches 37 are provided in the portion 30 on the other side of the diametrical longitudinal axis of the opening 28 for the reception of tie rods.

A bottom plate 38 is provided for one end of the stack and a top plate 39 provided for the other end of the stack, which plates are flanged as at 40 to extend over the peripheral edges of the stack. Rods 41 extend through the aligned openings 36 and notches 37 and are tied at their ends by means of heads 42 and members 43 so as to maintain the stack of members in substantially the position in which they are located while also preventing the members from expanding due to liquid absorbed. A reinforcing end plate 50 at each end may be used. This manner of placing the rods 41 closely adjacent the center of opening 28 and through the large supporting area and the overlapping parts of the members 26 serves to very nicely and effectively support the stack and hold it against warping.

The stack with its end plates is assembled over the center tube 11 and rests upon an abutment 45 at the lower end and is pressed downwardly onto this abutment by a spring 46 acting between the cover and the other end of the element. Liquid which surrounds the element will pass in through the cells between the portion 28 of the members 26 passing through the members 26 and to the center opening 28 and thence out

through opening 47 in the center tube downwardly from the center tube and out of the filter. This opening 47 also maintains the level of oil in the casing when the circulation to the casing stops.

The die is very simple for cutting out the sheet members which form the structure.

I claim:

1. A cell type filter element comprising a stack 10 of sheet members of identical configuration, each member having an opening for registering with a like opening in the next member, and each member having a web portion radiating from said opening throughout substantially 180° of arc from the center of said opening to the periphery 15 of said element and radiating a lesser amount oppositely to enclose said opening, adjacent members being oppositely disposed to form cells between like positioned members on opposite 20 sides of a diametrical line through the center axis of the element and with the portions surrounding the openings overlapping to provide the cell spacing.

2. A cell type filter element as in claim 1 25 wherein said members are each self-supporting.

3. A cell type filter element as in claim 1 wherein said openings are out of round in shape to provide a means for aligning said members.

4. A cell type filter element as in claim 1 30 wherein rods extend through said stack of members between the periphery of the element and the center of said opening and through a portion of each of said members.

5. A cell type filter element as in claim 1 35 wherein rods extend through said stack of members between the periphery of the element and the center of said opening and through a portion of each of said members where they overlap.

GEORGE D. BURLEY.
